Primary Examiner — Dominic Simone(74) *Attorney, Agent, or Firm* — Fross Zelnick Lehrman & Zissu, Esq.; Lawrence E. Apolzon, Esq.(57) **CLAIM**

The ornamental design for footwear, as shown and described.

DESCRIPTION

FIG. 1 is a front perspective view of a shoe showing my footwear design; FIG. 2 is a left side view of the footwear shown in FIG. 1; FIG. 3 is a right side view of the footwear shown in FIG. 1; FIG. 4 is a front view of the footwear shown in FIG. 1; FIG. 5 is a rear view of the footwear shown in FIG. 1; and, FIG. 6 is a top view of the footwear shown in FIG. 1. The broken line showing of the sole, heel, heel cap and heel cup are shown for environmental purposes and form no part of the claimed design.
